UNITED STATES PATENT OFFICE

EDWARD E. DENLER, OF MEXICO CITY, MEXICO

MANUFACTURE OF CARDBOARD CONTAINERS

Application filed December 13, 1929, Serial No. 413,869, and in Mexico January 15, 1929.

The present invention relates to improvements in the manufacture of card board containers, and more especially of those used for face powder, in which the powder is kept in a separate box placed inside of the container and closed on top with a paper cover to be torn before extracting the powder.

The invention has for its object to provide an improved method for manufacturing these inner boxes, by reducing the number of the different steps of operation. Another object of the invention is to facilitate the introduction of said inner box into the container, while producing a close fit, by reducing the diameter of the lower edge of said box by means of a suitably shaped die.

The invention is illustrated in the accompanying drawings in which:

Figure 1 is a side view, partly in section, of the complete container for face powder.

Figure 2 is a side view, also partly in section, of the inner box containing the powder.

Figure 3 illustrates the manner in which the paper cover and the lining of the inner box are jointly applied.

Figure 4 shows the card board or paper strip used for lining the box.

Figure 5 shows the paper disc forming the cover.

Figure 6 represents the lining of a box as actually manufactured, formed by a strip of card board having been wound around a mandrel.

Figure 7 shows the ring formed as shown in Figure 6, with the paper cover glued to one of its edges.

Figure 8 illustrates the operation of compressing the free edge of the inner box for facilitating its introduction into the container.

In the drawings, in which similar reference characters refer to similar parts throughout, 1 indicates the lower part of the container, 45 in which is placed the inner box 2, higher than part 1, and closed above by a paper disc 3. The container is provided with a cover 4, put over the projecting part of box 2.

The powder placed in the container lies 50 between the paper cover 3 and the bottom

of part 1, said paper cover being torn for extracting the powder.

The improvements forming the object of the present invention refer exclusively to the manufacture of the inner box 2. As actually manufactured, this box consists of a rolled up paper or card board strip forming the body of the box, with the inside lining formed by another rolled up paper strip 5 (Figure 6), to one of the edges of which is glued the paper cover 6, as shown in Figure 7. Obviously, the introduction of the lining 5 is rather difficult if a tight fit is to be obtained, which however is necessary for spreading evenly the glue which holds the two parts together. It happens therefore frequently that the paper cover is torn while trying to introduce the lining.

According to the invention, the paper cover 3 and the inner lining of box 2 are applied in one operation. The box 2, which provisionally only consists of a ring of rolled up card board, with one of its edges 2^a curled inwardly in a manner already well known, is placed within the circular opening of a plate 7 and rests with its curled edge on another lower plate 8. On top of said ring 2, in a recessed portion of plate 7, is placed a paper disc 3 having a larger diameter than the ring, the recess in said plate serving to center said disc. Around a plunger 9, raised above said ring 2, is rolled a paper or card board strip 10, of a length substantially equal to the inner periphery of ring 2, a small quantity of glue having first been applied to the inside of said ring.

The plunger 9 is then forced downward and pushes the paper disc 3 before it, until it comes to rest against the inwardly curled edge 2^a, its turned up flange adhering to the inside of the ring 2 by the glue it has carried with it. The plunger 9, on its downward stroke, also pushes the strip 10 into the ring 2, thereby lining it, after which the plunger is withdrawn, leaving the lining glued to the ring, with the flange of the paper cover placed between said ring and the lining.

The box being thus assembled, is placed again into a hollow plunger 11, with the paper cover 3 up, and is pressed with its lower

free edge against a reducing die formed by a plate 12 having a circular groove 13 with a sloping outer wall. By the pressure against this die, said lower edge is compressed inwardly, thereby reducing its diameter so as to facilitate the introduction of the box 2 into the container 1. The lining 10 is preferably a little shorter than the height of said box, so as to permit its lower edge to be compressed 13 as described.

While the aforesaid improvements in the manufacture of containers are shown and described as applied to round containers for face powder, it is understood that the same 15 may also be carried out in the manufacture of any other kind of containers.

What I claim is:

1. A method of securing in one operation a paper cover and an inside lining to the body portion of a box with an open bottom, which consists in placing a disc of paper concentrically over said box, applying glue to the inside of said box, pushing said paper disc down by a plunger which carries with it the lining material, and compressing the edge of the box opposite to the paper cover.
2. The method of securing in one operation a paper cover and an inside lining to the body portion of a box with an open bottom and with one of its edges curled inwardly, which consists in placing the box with the curled edge downward, applying glue to the inside of said box, placing a paper disc concentrically on top of said box, winding a strip of lining material of substantially the same length as the inner periphery of said box around a plunger, pressing down said plunger so as to push before it the paper disc and carry with it the lining, down to the curled 40 edge of the box, and reducing the diameter of the edge of the box opposite to the paper cover by means of a separate reducing die.
3. The method of securing in one operation a paper cover and an inside lining to the body portion of a box with an open bottom and with one of its edges curled inwardly, which consists in holding the box with the curled edge downward, applying glue to the inside of said box, placing a disc of paper of larger diameter than the box concentrically over its upper edge, winding a strip of lining material of substantially the same length as the inner periphery of said box around a plunger, pushing said paper discs 55 and said lining into said box by means of said plunger, placing the box with the paper cover up in a hollow plunger, and compressing its edge opposite to the paper cover in a die formed by a groove with a sloping outer wall.

In testimony whereof I affix my signature,
EDWARD E. DENLER.
